(57) **CLAIM**

The ornamental design for a cup lid, as shown and described.

DESCRIPTION

FIG. 1 is a perspective view of a cup lid according to a first embodiment of the design.

FIG. 2 is a top view of the cup lid of FIG. 1.

FIG. 3 is a bottom view of the cup lid of FIG. 1.

FIG. 4 is a left edge view of the cup lid of FIG. 1.

FIG. 5 is a right edge view of the cup lid of FIG. 1.

FIG. 6 is a front edge view of the cup lid of FIG. 1.

FIG. 7 is a rear edge view of the cup lid of FIG. 1.

FIG. 8 is a perspective view of a cup lid according to a second embodiment of the design.

FIG. 9 is a top view of the cup lid of FIG. 8.

FIG. 10 is a bottom view of the cup lid of FIG. 8.

FIG. 11 is a left edge view of the cup lid of FIG. 8.

FIG. 12 is a right edge view of the cup lid of FIG. 8.

FIG. 13 is a front edge view of the cup lid of FIG. 8; and, FIG. 14 is a rear edge view of the cup lid of FIG. 8.

Structure shown in broken lines is not a part of the claimed design, but is included to show the environment in which the claimed design is typically associated.
